UNITED STATES PATENT OFFICE.

HENRY UNTERMEYER, OF NEW YORK, N. Y.

DESIGN FOR A WATCH-CASE.

SPECIFICATION forming part of Design No. 12,451, dated September 6, 1881.

Application filed August 4, 1881. Term of patent 3½ years.

To all whom it may concern:

Be it known that I, HENRY UNTERMEYER, of the city, county, and State of New York, have invented a new and Improved Design for 5 Watch-Cases, of which the following is a specification.

The photographic illustration is a front elevation of my newly-designed watch-case.

The leading feature of my design consists in 10 the representation of a horse and jockey, the horse being shown as standing upon a race-track having a grass border along its farther edge.

Another feature of my design consists in a 15 ring of dots formed along the inner edge of the beveled border of the lid.

A represents a side or lid of a watch-case, upon the middle part of which is formed the figure B of a horse with a jockey, C, mounted 20 upon him. The horse B is shown as standing upon a race-track, D, having a grass border, E, along its farther edge. The lid A of the case is made with a beveled outer part or border, which has a ring, F, of leaves or shells 25 formed upon it. Upon the lid A, along the in-

ner edge of the border F, is formed a ring of dots, G, as shown in the photograph.

Having thus described my invention, I claim as new and desire to secure by Letters Patent—

1. The design for a watch-case herein shown 30 and described, the same consisting of the representation of the horse and the jockey mounted thereon, the horse being shown as standing upon a race-track having a grass border.

2. The design for a watch-case herein shown 35 and described, the same consisting of a circular lid having a ring of dots along the inner edge of its beveled border.

3. The design for a watch-case herein shown 40 and described, the same consisting of the representation of the horse and the jockey mounted thereon, the horse being shown as standing upon a race-track having a grass border, and the horse-jockey and track surrounded by a ring of dots and an ornamental border.

HENRY UNTERMEYER.
